ATTORNEY

UNITED STATES PATENT OFFICE.

WILLIAM NELSON HEAD, OF NEW YORK, N. Y.

DESIGN FOR A COFFEE-POT.

SPECIFICATION forming part of Design No. 30,614, dated April 25, 1899.

Application filed March 16, 1899. Serial No. 709,339. Term of patent 7 years.

To all whom it may concern:

Be it known that I, WILLIAM NELSON HEAD, a citizen of the United States, and a resident of New York, (Brooklyn,) county of Kings and 5 State of New York, have invented and produced a new and original Design for Coffee-Pots, of which the following is a specification, reference being had to the accompanying drawing, forming a part thereof, in which 10 similar letters of reference indicate corresponding parts.

The figure is a side elevation of a teapot, showing my new design.

As shown in the drawing, the leading or 15 material feature of my design consists in a series of ribs *a* and of beads *b*, the said ribs and said beads being convex in cross-section and disposed or arranged as shown in the figure.

20 The spout *c* has a series of convex ribs *d*, disposed as shown.

A chased band *e* encircles the upper edge of the pot.

The main body of the pot is left plain, as shown at *f*.

It is apparent that this design is also applicable to coffee or hot-water pots.

Having described my invention, what I claim as new, and desire to secure by Letters Patent, is—

30 The design for a coffee-pot, as herein shown and described.

In testimony that I claim the foregoing as my invention I have signed my name, in presence of two witnesses, this 13th day of March, 35 1899.

WILLIAM NELSON HEAD.

Witnesses:

V. B. W. BENNETT,
B. McCOMB.
